US00D491293S

(12) United States Design Patent (10) Patent No.: **US D491,293 S**
Tada et al. (45) Date of Patent: **** Jun. 8, 2004**

(54) **REAR COMBINATION LAMP FOR AN AUTOMOBILE**

2002 BMW 745i; Imported Cars Guide Book 2003; Oct. 29, 2002; Front and back cover pages, and p. 62.

(75) Inventors: **Hiroyuki Tada**, Aichi-ken (JP); **Yasuhide Hamano**, Toyota (JP)

* cited by examiner

(73) Assignee: **Toyota Jidosha Kabushiki Kaisha** (JP)

Primary Examiner—Marcus A. Jackson

(**) Term: **14 Years**

(74) Attorney, Agent, or Firm—SAIDMAN DesignLaw Group

(21) Appl. No.: **29/185,394**

(57) CLAIM

(22) Filed: **Jun. 26, 2003**

The ornamental design for a rear combination lamp for an automobile, as shown and described.

(51) LOC (7) Cl. **26-04**

DESCRIPTION

(52) U.S. Cl. **D26/28**

(58) Field of Search D26/28-36; 362/61, 362/80, 81, 82, 83, 83.3, 267, 269, 275, 330-340

FIG. 1 is a front perspective view of a rear combination lamp for an automobile showing our new design;

(56) References Cited

FIG. 2 is a front view thereof;
